(57) **CLAIM**

The ornamental design for a digital video camera, as shown and described.

DESCRIPTION

FIG. 1 is a front view of a digital video camera showing my new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a rear, top and left perspective view thereof;

FIG. 8 is a rear and top perspective view thereof; and,

FIG. 9 is a rear, bottom and left perspective view thereof.

The dash-dotted broken lines in drawings define the bounds of the claimed design; the evenly spaced broken lines show the digital video camera; all broken lines form no part of the claimed design.

1 Claim, 9 Drawing Sheets
